APRON OR SIMILAR ARTICLE

Anna Louise S. Carroll, North Tarrytown, N. Y.

Application December 20, 1947, Serial No. 143,251

Term of patent 3½ years

(Cl. D3—26)

To all whom it may concern:

Be it known that I, Anna Louise S. Carroll, a citizen of the United States of America, residing in North Tarrytown, county of Westchester, State of New York, have invented a new, original, and ornamental Design for an Apron or Similar Article, of which the following is a specification, reference being had to the accompanying drawing, forming part thereof.

In the drawing the figure is a plan view of an apron or similar article, embodying the design.

The characteristic feature of my design resides in the combination on the apron disclosed of the specific detachable, quilted pot holder pockets arranged on the skirt portion as shown.

I claim:

The ornamental design for an apron or similar article, substantially as shown and described.

ANNA LOUISE S. CARROLL.
